(57) **CLAIM**

The ornamental design for a nonwoven fabric, as shown and described.

DESCRIPTION

FIG. 1 is an isometric view of a nonwoven fabric showing our new design;

FIG. 2 is a top plan detail view of area 2 circumscribed within FIG. 1;

FIG. 3 is an isometric rear view of the design of FIG. 1;

FIG. 4 is a rear plan detail view of area 4 circumscribed within FIG. 3;

FIG. 5 is an isometric view of a second embodiment of our new design;

FIG. 6 is a top plan view thereof;

FIG. 7 is an isometric rear view thereof;

FIG. 8 is a rear plan view thereof;

FIG. 9 is an isometric view of a third embodiment of our new design;

FIG. 10 is a top plan view thereof;

FIG. 11 is an isometric rear view thereof; and,

FIG. 12 is a rear plan view thereof.

The pattern of the design repeats uniformly throughout the surface of the nonwoven fabric. The broken lines forming an edge surrounding the design represent the boundaries of the nonwoven fabric and form no part thereof. The dot dash dot broken lines circumscribing the details in FIGS. 1–4 form no part of the claimed design.
